Inventor:
John Frier
By G. Henry Kneely,
His Attorney.

UNITED STATES PATENT OFFICE

JOHN FRIER, OF UNIVERSITY CITY, MISSOURI

DISPLAY CABINET

Application filed February 23, 1926. Serial No. 89,916.

My invention relates to display cabinets and more particularly to display cabinets which are adapted to be placed on a store counter so that the goods contained therein will be brought to the attention of customers and may be inspected by them.

Heretofore these display cabinets have been made in various forms and have embodied various expedients for displaying the merchandise but no cabinet has heretofore been devised which is adapted to contain a plurality of styles or sizes of a unit of merchandise and which will display the different styles or sizes of these units so that a customer may easily make his selection without removing the merchandise from the cabinet and yet the article selected may be quickly and easily delivered by the sales clerk. Some of these cabinets have been made with a glass 20 panel in the top or front thereof and with a compartment, separate from the rest of the interior of the cabinet, formed adjacent this transparent panel and adapted to receive for display the various styles of merchandise. 25 This construction is objectionable for two reasons, namely, first because the clerk must either turn the cabinet or must go to the front of the counter to see which unit is selected by the customer; and, second, because 30 usually all or a large part of the merchandise must be removed from the cabinet to find a particular style or size wanted.

The object of my invention is to provide a cabinet which is of an attractive design, which 35 permits an easy inspection and selection of any one of the styles and sizes of the merchandise contained therein, and which also permits easy withdrawal of the merchandise from the cabinet after a selection of a certain style and size has been made by the customer.

With these and other objects in mind my invention is fully shown in the accompanying drawings wherein similar letters are used 45 to designate similar parts: Fig. 1 is a perspective view of the front of one embodiment of my new and improved display cabinet when in use; Fig. 2 is a back view; and Fig. 3 shows in detail a unit of merchandise to be displayed in the cabinet.

Referring to the figures, A is a casing which has a transparent top and front and which is preferably made of glass or other transparent material. This casing is open at its back as shown in Fig. 2 and, preferably, has the 55 front, top, bottom and ends formed integral with one another. On the bottom of the casing are feet B, preferably tipped with rubber or felt, by which the casing is normally supported when placed on a counter. The interior of the casing A is divided into a plurality of compartments preferably by means of a plurality of separably removable containers C which are adapted to fit therein and be moved into or out of the casing through the 60 open back thereof. As clearly shown in Fig. 2, when all of the containers are in place in the casing A their backs form a back wall for the casing. Also, when one of the containers is removed from the casing the adjacent side 65 walls of the adjacent containers keep dust and dirt from entering the containers which are left in the casing because of the close fit, as shown in the drawing, between the side walls 70 of the containers and the inner surfaces of the top, front and bottom of the casing. Each of the containers C is open at its top and front as 75 shown in Fig. 1 and is adapted to contain a number of pairs of shoe laces D or other units of merchandise. To more clearly show the 80 device and to avoid confusion in the drawings only one of the containers C is shown filled with merchandise in each of Figs. 1 and 2. The containers C are each provided with a knob E which may be gripped when the containers are moved. On the front of the casing A is arranged as at F, the name, brand, and trade-mark under which the goods are 85 sold. The letters and lines are preferably either cut in the transparent material of 90 which the front of the casing is made or formed so as to project outwardly from the front and made of transparent material for the purpose hereinafter set forth.

I prefer that each of the containers be filled 95 with a different type of the units of merchandise to be displayed in the cabinet, that is, that the units of merchandise are of different size, style or color, and that two groups of indicia designating the type of the unit of merchan- 100

dise be placed thereon. As stated above, in this embodiment of my invention the containers C are filled with pairs of shoe laces and each pair of shoe laces, as shown in detail in Fig. 3, is wrapped with a band G which has the size of the shoe laces within the band printed thereon at H and H' and with the group of indicia designating the size at H inverted with respect to the indicia at H'.

10 The color and style of the shoe laces is shown by the parts of the laces which project out past the ends of the sides of the band.

The use of my device is as follows: Each of the containers C is filled with units of merchandise which, as I have stated above, I prefer to be of different sizes or styles with only one size or style of the units of merchandise in each container. The merchandise is placed in the container so that one of the

20 groups of indicia designating the type will be readable from the front of the cabinet, as shown in Fig. 1, and the other group of indicia will be readable from the back of the container, as shown in Fig. 2. Since the 25 top and front of the casing A are transparent and each of the containers C is open at its top and front the merchandise in the container will always be visible from above and in front thereof without withdrawing the 30 container from the cabinet, thereby obviating the necessity of removing the merchandise from the cabinet and preventing it from being soiled by settling dust or by handling. Since the letters and lines formed on the 35 front of the display cabinet at F are transparent, all as described above, they will not interfere with the visibility.

I do not intend to limit my invention to the exact details of construction shown in 40 the drawings. The form and shape of the casing A and the containers C may be varied within wide limits as hereinafter claimed without deviating from the spirit of my invention. Likewise, the containers C may be 45 adapted to hold many different types of merchandise and if the containers are filled with units of merchandise which vary greatly in style or color it may be necessary to also have on each unit or on the wrapping thereof indicia arranged as described above to indicate the style or color thereof.

What I claim as new and desire to secure by Letters Patent, is:—

1. A display cabinet comprising a casing 55 having an open back and also a top and front formed of transparent material, a plurality of containers fitted into the interior of said casing and dividing said interior into a plurality of compartments, each of said 60 containers being adapted and arranged to hold merchandise and each having back, bottom and side walls and being open at its top and front, and said side walls being constructed and fitted to substantially prevent the 65 passage of dirt and dust between said

walls and the inner surfaces of the top, front and bottom of said casing.

2. A display cabinet comprising a casing having an open back and also having integral top, front and end walls of transparent material, a plurality of separably removable containers fitted into the interior of said casing and dividing said interior into a plurality of compartments, each of said containers being adapted and arranged to hold merchandise and each having back, bottom and side walls and being open at its top and front, and said side walls being constructed and fitted to substantially prevent the passage of dirt and dust between said walls and the inner surfaces of the top, front and bottom of said casing.

In witness whereof I have signed my name to this specification.

JOHN FRIER.
